UNITED STATES PATENT OFFICE.

FREDERICK A. READ, OF WEST HADDONFIELD, NEW JERSEY, ASSIGNOR TO
GERALDINE READ, OF WEST HADDONFIELD, NEW JERSEY, TRADING AS
PHILADELPHIA PAPER COMPANY, OF PHILADELPHIA, PENNSYLVANIA.

PAPER BAG.

SPECIFICATION forming part of Letters Patent No. 717,621, dated January 6, 1903.

Application filed September 22, 1902. Serial No. 124,328. (No model.)

To all whom it may concern:

Be it known that I, FREDERICK A. READ, a citizen of the United States, residing at West Haddonfield, in the county of Camden and 5 State of New Jersey, have invented certain new and useful Improvements in Paper Bags, of which the following is a specification.

My invention has relation to a bag made from paper or similar material; and in such 10 connection it relates to the construction and arrangement of a bag for inclosing trunks and other analogous articles or structures.

The principal object of my invention is to provide a bag having a flat base or bottom 15 united to a rectangular tube and especially adapted to cover packages having rectangular sides and ends—such as trunks, valises, or the like—to protect the same in shipping or storing.

20 To this end my invention consists, primarily, of a rectangular tube formed from a single sheet of paper or the like having its ends pasted along one of the sides of the tube and a bottom or base formed of a second sheet 25 of paper and united to the tube, the opposite side ends of the tube being infolded, so that the tube may be flattened and folded down upon the bottom or base of the bag, if required.

30 The nature and scope of my present invention will be more fully understood from the following description, taken in connection with the accompanying drawings, forming part hereof, in which—

35 Figure 1 is a perspective view of the tubular portion of the bag embodying main features of my invention and of the base or bottom detached from the tubular portion. Fig. 2 is a perspective view of the bag wholly 40 detested. Fig. 3 is an end elevational view of the bag, showing the tubular portion partly collapsed. Fig. 4 is a similar view showing the tube wholly collapsed. Fig. 5 is a perspective view of the bag, showing the tubular 45 portion wholly collapsed and folded down flat upon the bottom; and Figs. 6 and 7 are detail views illustrating the connection between the bottom of the bag and the sides and corners of the tubular portion of the bag.

Referring to the drawings, *a* represents the 50 base or bottom of the bag, consisting of preferably a rectangular sheet of paper or analogous material. The tubular portion *b* of the bag consists of a single sheet of paper or the like folded at four portions to form a rectangular tube and having its ends overlapping, as at *b'*, and pasted together along one of the rectangular sides of the bag. The tube *b* thus constructed has two larger rectangular sides and two smaller rectangular ends. The 55 ends are creased along a medial line *b*², extending at right angles to the base of the tube to the point *b*³, which is above the base or bottom *a* of the bag a distance corresponding to about one-half the width of the ends of the 60 tube. The ends are now creased along the diverging lines *b*⁴ and *b*⁵ to the corners of the tube *b*. The sides of the tube are also creased along the lines *b*⁶ and *b*⁷. As a result of the infolding of the ends of the bag along the 65 lines *b*², *b*⁴, and *b*⁵ and the sides along the lines *b*⁶ and *b*⁷ the tubular portion of the bag may be collapsed to assume successively the 70 positions illustrated in Figs. 3, 4, and 5. In the position illustrated in Fig. 4 the upper 75 portion of the tube *b* projects at right angles from the lower portion, which is infolded and flattened down upon the base or bottom *a*. In Fig. 5 the upright upper portion of the 80 tube is further flattened down into a plane parallel with the base or bottom *a*.

In Figs. 6 and 7 the connection between the lower open end of the tube *b* and the bottom *a* is illustrated in detail. It consists in forming two side flaps by infolding the lower 85 edges *b*⁸ of the two longer sides of the tube *b* after the tube has been collapsed, as illustrated in Figs. 4 and 5, then inserting the bottom *a* into the grooves formed by these infolded edges *b*⁸, and thereafter pasting the bottom *a* to the lower edge of the ends of the tube, as at *b*⁹, and finally pasting the flaps formed by the infolded edges *b*⁸ down upon the under face of the bottom *a*.

Having thus described the nature and object of my invention, what I claim as new, and desire to secure by Letters Patent, is—

A bag, comprising a tube formed from a

sheet of paper or the like having its ends secured together, a bottom formed of a second sheet of paper or the like, flaps bent inwardly from the lower edges of two of the sides of the tube and arranged to be secured to the under face of said bottom and flaps projecting from the lower edges of the opposite side ends of the tube and arranged to be secured to the upper face of said bottom, said opposite side ends of the tube being creased so

that the ends may be infolded and the tube flattened down upon the bottom.

In testimony whereof I have hereunto set my signature in the presence of two subscribing witnesses.

FREDERICK A. READ.
